SCRAPER FOR WINDSHIELDS

John Sinko, Oak Park, Ill., assignor to Sinko Mfg. &
Tool Co., a corporation of Illinois

Application October 24, 1956, Serial No. 43,502

Term of patent 14 years

(Cl. D9—6)

FIG. 1

FIG. 2

FIG. 3

FIG. 4

Figure 1 is a bottom plan view of a scraper for windshields embodying my new design;

Fig. 2, a side elevational view;

Fig. 3, a top plan view; and

Fig. 4, an end elevational view as seen from the right of Fig. 2.

I claim:

The ornamental design for a scraper for windshields, as shown.
